UNITED STATES PATENT OFFICE

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY

PHOTOMETER

Application filed January 3, 1928. Serial No. 244,100.

My invention relates to improvements in photometers and has for one object to provide a new and improved form of portable photometer wherein the determination of light intensity, either in terms of beam candle power or foot candle power as the case may be, is made by comparison with darkness rather than light, by the use of an adjustable shutter of progressive degrees of opacity.

10 My invention is especially adapted for use in connection with the determination of candle power of locomotive electric head lights and the like, but it is obvious that it might be used with equal convenience in many other circumstances.

15 My invention is illustrated more or less diagrammatically in the accompanying drawings, wherein—

Figure 1 is a plan view;

20 Figure 2, a section along the line 2—2 of Figure 1;

Figure 3, a section along the line 3—3 of Fig. 1;

Figure 4, a side elevation;

25 Figure 5, a plan view of the variable element;

Figure 6, a plan view of the bottom floor of the housing of the apparatus.

30 A is the floor or bottom plate. It is provided with a lug A¹ adapted to interlock with the cylindrical wall A² of the housing A³ to form a flat, cylindrical receptacle, the inside of which is coated with light-absorbing material. The interlocking of the lug A¹ with 35 the wall A² centers the bottom floor A in position. This is important, because on it is mounted a reflector A⁴. This reflector may be an inclined mirror or a prism, as the case may be, but in either case is rigidly and permanently positioned on the floor A and is 40 surrounded by a housing open at the top and provided with a small aperture A⁵ through which light rays coming in from the top may be reflected outwardly across the axis of the cylindrical housing.

45 In that part of the cylindrical wall A² in line with the opening A⁵ is a sleeve B, in which is slidably mounted an adjustable tube B¹ having an eye-piece B² apertured at B³. The bottom of the tube is closed by a wall B⁴

apertured at B⁵, the apertures B³, B⁵ and A⁵ being all in line and serving merely to prevent anything except the light rays directly reflected from the reflector or mirror reaching the eye of the observer when he places it 55 against the cup.

The cover A³ is apertured immediately above the reflector. In this aperture is threaded a cup C closed at C¹ but the closure being apertured at C². C³ is a glass closing 60 the cup and overlying the aperture, C⁴ a packing ring engaging the glass and associated with the band C⁵ to lock the glass in place and make a dusttight closure for the receptacle. C⁶ is packing carried by the bottom of the cup to prevent light entering laterally into the housing.

D is a supporting wheel having a threaded shank D¹ engaging in threaded relation the hub D². The hub D² carries a knarled adjusting hand wheel D³ and the parts are arranged, when shown in position as in Fig. 2, so that the hub D² makes a tight bearing with the aperture in the cover so as to permit rotation of hub and wheel. Mounted on the supporting wheel D is the circular shutter D⁴, which may be made of glass, celluloid, or any other suitable material. Arranged intermediate the outer periphery of this shutter and its center of rotation is a light interfering band D⁵, made of varying degrees of opacity from zero opacity to 100 per cent. The parts are so arranged that this band lies beneath the aperture C² and all light entering through that aperture, to reach the reflector, must pass 85 through it. The packing above referred to around the cup C insures that there will be no reflected light leaking into the photometer housing without passing through the interfering shutter. Arranged about the outer periphery of the shutter D⁴, and in register with the varying degree intensity of the shutter, is a numerical scale which may be calibrated on any desired basis, either arbitrary 90 or not, as the case may be, but which scale bears some relation to the intensity of the light interference element.

The housing is apertured at E in line with this scale. E¹ is a window closing this aper- 100

ture and E² a frame whereby this window may be locked in place.

The use and operation of my invention are as follows:

5 The operator first draws out the slide to its full extension, then points the top of the photometer toward the light which he wishes to measure. The light passing in through the aperture in the top travels through the variable shutter, reaches and is reflected from the reflecting surface through the three apertures in three parallel walls to the eye of the observer. The small openings cut down the exposed surface and neutralize all differences 10 in eye-sight, so that any one who can see at all can make the determination.

Since the interior of the housing is dead black, since only a very thin pencil of light passes to or is reflected from the housing, and 15 since the light that the observer sees is the small round hole in the middle of the wall between him and the reflector, all he sees is a round disk of bright light in contrast with the dead black background. If the operator 20 then rotates the hand-wheel on the outside of the housing, bringing an increasingly opaque part of the shutter into line with the opening leading to the reflector, he will finally reach a point where all light is shut off and where 25 he can not see any light in the photometer at all. This can be checked by rotating the hand-wheel in the opposite direction until light is seen and then returning it until the light disappears. Experience shows that 30 a number of observations of this kind with the opaque shutter set to just completely cut off light results in giving a very accurate determination of the beam or foot candle power.

35 I claim:

A photometer comprising a flat cylindrical housing, one of the curved walls being apertured, a tubular socket located within said aperture and extending into the housing, 40 an eye piece tube thereon, a reflector in line with the axis of the eye piece, a wall projecting upwardly from the base of the reflector, a plurality of walls associated with the reflector being apertured in line, a light 45 opening in one of the flat walls of the housing in register with the reflector, a shutter mounted on the flat wall of the housing of varying opacity and a hand wheel projecting through the wall whereby this shutter may be adjust- 50 ed to mask with progressive degrees of opacity the light opening, a reading scale on the shutter, the wall of the reflector being apertured in register with said scale to permit determination of the shutter position by the use 55 of said scale.

Signed at Chicago county of Cook and State of Illinois, this 28th day of December, 1927.

CHARLES W. DAKE.
